CEMENT GROUT MIXING AND DISTRIBUTING MACHINE

George Wentworth Grayson, Darling Point, near Sydney, Australia, assignor to John Thomas McKee, Sydney, Australia

Application January 6, 1934, Serial No. 705,489
In Australia January 16, 1933

2 Claims. (Cl. 83—73)

This invention relates to cement grout mixing machines of the type designed to supply a cement and sand and water mix having devices to enable the maintenance of the sand content of the grout at a predetermined ratio irrespective of any moisture created variation of the sand volume and having devices to prevent segregation of the grout constituents while being conveyed from grout mixing apparatus to the point of application.

A machine of the type referred to consisted of a proportioning mill having a separate hopper for sand and cement each having a gravity discharge, having revolvable vanes in the orifice of said discharge and having a shutter slidable on said vanes; a mixing trough juxtaposed immediately below the proportioning mill, having on a rotatable shaft therein a multiplicity of mixing and conveying paddles and having a gravity discharge, and having a water pipe with delivery nozzles juxtaposed above said mixing paddles; an agitating and distributing trough having a swivel connection to said mixing trough discharge and having a rotatable shaft therein and having a multiplicity of helically arranged agitating and conveying paddles on said shaft; mechanism being provided to rotate said vanes and the mixing and conveying devices.

In such machines used heretofore it has been necessary to rely upon an operator to make periodic tests of the grout mix and by instruments involving some knowledge of mathematics to vary the allocation of one or other of the grout constituents to maintain the correct proportioning thereof. Such machines have proved more or less satisfactory in practice having overcome prejudice to the use of a cement grout founded on previous failures of it (occurred generally by incorrect proportioning of cement and sand due to the moisture created changes in the weight per unit volume of the sand, faulty mixing, absence of time control of mixing and segregation of the mix) and have established the use of cement grout in road construction and in the ballasting of tram per-ways and encouraged inquiries as to the use of cement grout in other fields of industry, as, for example, in canal and irrigation channels, and retaining walls and like concrete work. Experience has proved however that operators cannot be relied upon to adjust the machine to continuously correctly allocate the grout constituents, for the sand volume in the different supplies to the machine is constantly altering and tests of the concrete produced by such machines have shown substantial variations

in crushing stresses due entirely to mishandling of the machines. Further the distributing troughs in machines heretofore have not been as effective as is desirable, owing to pebbles and the like jamming between the conveyer and the trough, resulting in stoppage of the machine with consequent dislocation of work and spilling of the grout.

Now this invention has been especially devised to provide a cement grout mixing machine which will at all times automatically produce a cement grout having a predetermined sand content irrespective of any moisture content or voids in the sand or bulking thereof, and it has been further devised to provide a combined mixer and distributor wherein the cement is retained until it changes to a gelatinous condition and wherein the sand particles and/or other grout constituents are effectively coated with the cement, conveyors liable to blockage being eliminated.

The previous machine made use of the known physical property of sand namely:— that although a given quantity of sand containing the usual moisture content occupies a greater volume than the same quantity when dry and rammed, when completely inundated it resumes its dry loose volume;

but only to test the composition of the grout subsequent to the mixing thereof. In this present invention this same property of the sand is utilized prior to the mixing of the grout to assure a precise predetermined composition of grout which remains invariable irrespective of weather conditions.

The principal characteristics of the improved cement grout mixing machine are devices to inundate sand in combination with mechanism to measure inundated sand and to measure cement and a rotatable frusto-conical mixing and distributing drum having an inlet at one end and a discharge at the other end, with mechanism to vary the inclination of said drum and to enable it to be swivelled laterally.

But in order that this invention may be readily understood and carried into practical effect it will be described with reference to the drawings accompanying and forming part of this complete specification. Fig. 1 is a longitudinal elevation and Fig. 2 is a plan of the general arrangement of the machine. Fig. 3 is a longitudinal elevation. Fig. 4 is a plan of the machine incorporating certain modifications.

Referring to Figs. 1 and 2 the machine is constituted of a wheeled chassis 7 with or without

- ordinary steering and propelling mechanism. Mounted on the chassis 7 is a sand bin or boot 8 and a cement bin or boot 9. Casings 10 and 11 extend from the boots 8 and 9 to a discharge hopper 12 and contained within said casings are endless bucket elevators 13 for sand and 14 for cement, erected and adjusted as well understood.
- The elevators 13 and 14 are for the purpose of proportioning the quantities of the sand and 10 cement and to raise these materials and deliver them to the discharge hopper 12. They are of the usual bucket type and each is driven independently from sprockets 15 and 16 on the counter shaft 17. The sprocket 15 drives the sand 15 elevator 13 through sprocket 18 and the sprocket 16 drives the cement elevator 14 through the sprocket 19. The sprockets 18 and 19 are driven from a prime motor by an ordinary gear train. The sprocket 19 may be changed to vary the 20 amount of cement delivered by the elevator 14 according to the sand to cement proportions required or alternatively the number or the size of the buckets may be varied to achieve the same purpose.
- 25 A pump 20 is provided to deliver water to the boot 8 through pipes 20A to inundate sand therein. This water after inundating the sand becomes the mixing water for the cement grout. Almost all this water (which will approximately 30 equal the volume of voids in the sand) will be lifted by the sand elevator buckets 13 and discharged with the sand into the hopper 12. Excess inundation water will overflow the boot 8 into pipe 21 which is a suction pipe for a pump 35 22 delivering through pipe 23 into the discharge end of the hopper 12 to be used if required in the mixing of the grout.
- The discharge hopper 12 delivers by gravity 40 flow the sand, cement and water to a swivel hopper 24 which in turn deposits it in a mixing feeder 25 wherein a helical conveyor mixes the ingredients and delivers them into a mixing and 45 distributing drum 27. The swivel hopper 24 is supported from the pivot 28 which in turn is fixed to the inner circle 29 of a turntable 30 supported by the members 31 and 32 fastened to the standards 33. The conveyor 26 is driven by shaft 34 which is affixed to the mixing drum 27 by a spider indicated at 35 and is rotated with said drum 27. 50 The mixing and distributing drum 27 is a hollow frustum of a cone its small end being about one-third the diameter of its large end and it is of sufficient length to give the correct periods of wetting and mixing of the ingredients as well as 55 provide reach for distributing the grout. The drum has its axis lying at such an angle that its bottom is approximately horizontal to prevent natural gravity flow towards the discharge end thereof. Attached to the inner wall of the drum 60 are one or more longitudinal vanes 26A provided to lift (assisted by the centrifugal force engendered by the rotation of the drum) the grout materials in the drum as it is rotated and to cause them to drop on reaching the top centre 65 of rotation. Owing to the inclination of the drum's axis the dropping ingredients are advanced along the drum an amount corresponding to the tangent of the angle of inclination multiplied by the diameter. The rotation of the 70 drum causes the material therein to roll and this action combined with the compulsory drop provides a thorough mixing of the ingredients. The drum may also have a plurality of annuli placed at equal distances therealong to constitute 75 rearders to the free flowing of the grout.

The drum 27 is rotated at a suitable speed but the peripheral speed must not be such that the centrifugal force imparted to the grout will exceed the weight of it. The rotation is effected by gearing 37 and 38, universal rod 39, gears 40, 41 and sprockets 42, 43 driven through a clutch (not shown) by shaft 45 from bevel gear 46, which in turn is driven by pulley 47 from engine pulley 48 through belt drive 49. This mixing and distributing drum 27 is supported on rollers 52 in 10 cage 53 which in turn is supported by balancing springs 54 attached to hook 55 on the standard 15 33. The cage 53 is rigidly mounted in a cradle which can swivel about the vertical axis of the swivelling hopper 24.

The framework 56 of the cradle is fixed at one end to the swivel hopper 24 and at its other end has an adjustable suspension rod 57 anchored to hook 55 and provided with a hand wheel 59 to enable adjustment of the inclination of the drum 20 27. A removable standard 60 is provided to support the drum 27 when not in use.

The grout discharge hopper 61, which receives the grout from the drum 27, is attached to the framework 56 and delivers the grout through the 25 throat 62 into the distributing chute 63. This distributing chute 63 tips at will of the operator on the pivot 64 and can be swung laterally on the swivel 65 the whole being supported from the discharge throat 62. The distributing chute 63 is 30 balanced by weight 58.

It will be seen that the anchorage 55 for the suspension rod 57 and the balancing springs 54 are vertically above one another and therefore have the same axis of rotation as the swivel hopper 24 and the drum 27.

In the modified construction depicted in Figs. 3 and 4 the separate sand and cement boots 8 and 9 and the elevators 13 and 14 therefor with operating mechanism and the mixing feeder 25 are 40 dispensed with.

In place of the noted integers is a measuring receptacle 66 of uniform cross section, (for example square) having above the measuring portion a hopper mouth 67 (to facilitate the filling 45 and discharge) and in said receptacle is a scale 68. Trolley wheels 69 have axles fixed to the back wall of the receptacle 66 and guides 70 provided on the chassis. Hoisting cables 71 anchored to the receptacle 66 are reeved through pulleys 72 50 on standards 73 and pass to winding drums 74 operated by an ordinary train of gears from the prime motor, clutches and brakes being provided as well understood. Operation of the hoisting gear lifts the measuring receptacle 66 and tips it 55 as indicated at 75.

Juxtaposed the tipping position of the receptacle 66 is a mixing mill 76 having on a spider 77 on a rotating spindle 78 a multiplicity of vanes 79 set at angles of approximately 30° off the horizontal and said vanes 79 may have orifices there-in to assist thorough intermingling of grout constituents, and some of them are set at opposite angles also to create turbulence in stirring. The spindle 78 is rotated by gearing from the 65 prime motor as well understood. A valve 80 in the bottom of the mill is operated by lever 81 to open a discharge to a second mill 82 having similar agitating mechanism to that described for mill 76, but its discharge valve 83 is adapted to 70 be set by hand wheel 84 to regulate the discharge therefrom which passes to the swivel hopper 24 before described.

The delivery of the grout ingredients to the mixing and distributing drum 26 by the mecha- 75

nism illustrated in Figs. 1 and 2 has been described with reference to the respective integers of the machine. In the mechanism illustrated in Figs. 3 and 4, and assuming for example the making of a grout in the proportions of one cement to two and one half sand, (two cubic feet cement to 5 cubic feet sand will require about 13½ gallons of water) the receptacle 66 is first charged with the inundation water up to approximately 2½ cubic feet mark on the scale 68. The receptacle is next charged with sand up to the 5 cubic feet mark, after which it is charged with cement up to the 7 cubic feet mark. The inundator receptacle is now charged and is ready to be lifted by the cables 71 and tipped into the mixing mill 66 where the ingredients are agitated and stirred by the vanes 79 for at least one and a half minutes to enable the cement to reach a gelatinous state. After this period of mixing, the valve 80 is operated by the lever 81 and the grout is discharged into the second agitating mill 82 from whence it flows continuously (by adjustment of the hand wheel 84) and at the same time agitated to the swivel hopper 24 and then into the revolving distributing drum 27. The receptacle 66 can be operated sufficiently fast to normally keep the mill 82 charged.

In the mixing and distributing drum 27 the vertical inclination of its axis determines the grout consistency, which is important. It is necessarily determined by experiment with the particular cement and sand to be used and is fixed by turning the screw hand wheel 59. After the inclination has been determined, the spirit level 86 is adjusted to horizontal by altering the capstan screws 87, and the machine is then ready to work. When the machine is standing on uneven ground, the angle of inclination will change as the mixing drum 27 is traversed laterally (it can be swung through a horizontal angle of approximately 180°); if correction of this irregu-

larity of inclination is not cared for, variations in the volume and consistency of the grout will result. To control this grout consistency, the operator watches the lever 86, while manipulating the flushing chute 63 with the operating handle 88. As the bubble in the level 86 moves, the hand wheel 59 is turned in the direction necessary to bring the bubble back to its central position.

I claim:—

1. In a cement grout mixing and distributing machine, a frame, a movably mounted bearing, an adjustable support for the bearing pivotally connected to the frame, a rotatably mounted frusto-conical mixing and distributing drum having an inlet opening at its larger end and a discharge opening at the smaller end journaled in said bearing, adjustable guy rods connecting the discharge end of the drum and pivotally secured to the frame coaxially with the support for the bearing, means for elevating and lowering the discharge end of the distributing drum, and means for moving the drum horizontally about the inlet end thereof. 15

2. In a cement grout mixing and distributing machine, a frame, a movably mounted bearing, a support for the bearing pivotally connected to the frame, a hopper pivotally mounted on the frame for movement about a vertical axis, a rotatably mounted frusto-conical mixing and distributing drum having an inlet opening at the larger end communicating with the pivotally mounted hopper and a discharge opening at the smaller end, the drum being journaled in the said bearing, adjustable guy rods connecting the discharge end of the hopper and pivotally secured to the frame coaxially with the support for the bearing, means for elevating and lowering the discharge end of the drum, and means for moving the drum horizontally about the pivotal axis of the hopper. 35 40

GEORGE WENTWORTH GRAYSON.
